(57) **CLAIM**

The ornamental design for a night light, as shown and described.

DESCRIPTION

FIG. 1 is a perspective view of a new ornamental design for a night light;

FIG. 2 is a front elevation view of the night light of FIG. 1;
FIG. 3 is a rear elevation view of the night light of FIG. 1;
FIG. 4 is a left-side elevation view of the night light of FIG. 1;
FIG. 5 is a right-side elevation view of the night light of FIG. 1;

FIG. 6 is a top plan view of the night light of FIG. 1;
FIG. 7 is a bottom plan view of the night light of FIG. 1;
FIG. 8 is a perspective view of the second embodiment of our new ornamental design for the night light; and,

FIG. 9 is a front elevation view of the night light of FIG. 8
wherein the rear, left-side, right-side, top, and bottom views
are the same as those shown and described in FIGS. 3-7.
The broken lines shown represent unclaimed subject matter
and form no part of the claimed design.

1 Claim, 5 Drawing Sheets
